Attorneys*

UNITED STATES PATENT OFFICE.

HERBERT S. JANDUS AND JOHN RICHARD MORGAN, OF DETROIT, MICHIGAN.

DESIGN FOR AN IMPACT SECTION FOR A VEHICLE BUMPER.

Application filed February 8, 1928. Serial No. 25,286. Term of patent 14 years.

To all whom it may concern:

Be it known that we, HERBERT S. JANDUS and JOHN RICHARD MORGAN, citizens of the United States, residing at Detroit, in the county of Wayne and State of Michigan, has invented a new, original, and ornamental Design for Impact Section for Vehicle Bumpers, of which the following is a specification, reference being had to the accompanying drawing, forming part hereof, wherein—

Fig. 1 represents a plan view and Fig. 2

represents a front elevation. Our invention relates to the impact sections for a vehicle bumper and the support means and clamp plates, are indicated by dotted lines.

We claim:

The ornamental design for an impact section for a vehicle bumper, substantially as shown and described.

HERBERT S. JANDUS.
JOHN RICHARD MORGAN.
